United States Patent Office.

J. PLUMMER SMITH, OF BUFFALO, NEW YORK, ASSIGNOR TO HIMSELF AND HENRY CHANDLER, OF SAME PLACE.

Letters Patent No. 105,379, dated July 12, 1870.

IMPROVEMENT IN LIQUID-METERS.

The Schedule referred to in these Letters Patent and making part of the same.

I, J. PLUMMER SMITH, assignor to HENRY CHANDLER and myself, both of the city of Buffalo, in the county of Erie and State of New York, have invented certain new and useful Improvements in Liquid-Meters, of which the following is a specification.

My improvements relate to that class of liquid-meters in which differential or proportional valves are employed, whereby the quantity of liquid passed through the pipes is ascertained by the measurement of the relatively small quantity that passes through the smaller valve, between the size of the aperture of which and that of the larger valve a certain and known ratio always exists, whatever the position of the valves may be.

The invention consists of two parts, one of which relates to the particular construction and manner of operating the valves and the other to the measuring-wheel.

In the accompanying drawing—

Figure I is a central vertical section, with the valves represented fully open.

Figure II is an elevation of the valves in a closed position, looking at right angles from Fig. I.

Figure III is a sectional plan of the valves.

Figure IV is an enlarged detached view in elevation of the smaller valve, represented in the position it is when the large valve is fully open.

Figure V is a similar view of the same in the position it is when the larger valve is closed.

Figure VI is a vertical section of the measuring-chamber and wheel.

Figure VII is a fragmentary view, showing the cam for tilting the wheel.

Like letters of reference designate like parts in each of the figures.

A is the induction-pipe.

B, the seat and chamber of the main valve.

C is a bed-plate, preferably cast as a flange from the portion B, to which is hermetically secured, in any suitable manner, the dome or cap D, of glass or metal.

E is the main valve, of conical form, arranged vertically, and having a stem, e, extending from both top and bottom, and passing through guides f f, as shown, or in any other suitable way, the upper stem e being provided with a weight, G, at its top.

H is a hollow pillar, secured to the bed-plate, through which an exit-passage from the pillar is formed.

Near the upper end of this pillar the chamber h opens into the dome D through a small aperture, h', which forms the port of the small valve.

The surface of the pillar surrounding this aperture is faced, and has fitted to it an oscillating cam, I, which, as it operates, gradually opens and closes the aperture h', as will presently be explained.

This cam is provided with a horizontal stem or axis,

i, which passes through a suitable bearing, J, at the top of pillar H.

The projecting end of this axis is provided with a screw-thread and an adjusting-nut, i', by which to regulate the pressure of a spiral spring, i'', interposed between it and the end of the bearing, whereby the cam is kept in proper contact with the valve-seat or faced surface surrounding the aperture h'.

Motion from the valve E is transmitted to the cam by means of the jointed bars K L, the former being hinged to the end of an arm, M, pendent from the valve E, while the forked or slotted end of the latter is secured to the cam by means of a set-screw, n, screwing into the cam, as clearly shown in Fig. III, so as to cause the cam to oscillate as the valve E reciprocates.

The ratio or difference between the areas of the two valves being determined on, which may be of any desired proportions, the cam is formed and adjusted in the forked end of the arm L, so as to uncover, when the valve E is fully open, such a portion of the aperture h' (as shown in Fig. IV) as will form the required ratio with the open aperture of the main valve. The edge of the cam is then so shaped as to gradually cover and reduce the size of the aperture h' in the same proportion, and as the aperture of the main valve is closed by the descent of the valve E, until it entirely covers the aperture (as shown at Fig. V) at the moment the main passage is completely closed.

Knowing the relative sizes of the two valves, and measuring the liquid that passes through the smaller, the quantity that has passed through the larger is ascertained by simple calculation, and by constructing the registering-device accordingly, the passage of a representative unit quantity through the smaller valve will be indicated on the registering-dial by a unit expressing the actual quantity passed through the pipe.

The water or other liquid, as it escapes through the valve E into the dome D, passes thence, through an opening in the bed-plate, into the induction-pipe O, except the small quantity which is required for the small valve, which is discharged or conducted from the latter directly into the measuring-chamber, or through a pipe, s, therein, as shown in the drawing.

P represents this chamber, and

Q, the measuring-wheel, preferably composed of three buckets, q q q, as represented in Fig. VI.

The shaft r of this wheel projects outside through vertical slots t in the sides of the vessel, and has its bearings in brackets u u'.

One end of this shaft is provided with a screw, v, which engages with a wheel, v', from which motion is communicated to the train-gear w of the registering-device, which gearing and registering apparatus may be of any suitable or common construction.

The opposite end of the shaft has mounted thereon

a triangular cam, x , which rests and turns on the flat surface of the bearing u' .

The cam is made triangular, to correspond with the number of buckets in the wheel Q , a side being required for each bucket, and it is so arranged, with reference to the bearing surface, that while any one of the buckets is being filled, the side of the cam corresponding therewith will rest on the bearing and support the wheel.

The length of the sides of the cam is so regulated that, when any one of the buckets has received the required quantity of liquid, the weight of it will be just sufficient to cause it to tilt and empty its contents, the wheel making one-third of a revolution and resting, at this end, on the next adjacent side of the cam, while the buckets will have simply moved forward one degree, so as to change places with each other.

I prefer to use a three-bucket wheel, although a wheel with a greater number may be employed.

The quantity of liquid which each bucket holds before tilting constitutes one representative unit, which is registered in the usual manner, through the mechanism connecting the axis of the measuring-wheel with the registering-device, as hereinbefore described, whereby the actual quantity which has passed through the main pipe is correctly indicated.

What I claim as my invention is—

1. The aperture K and oscillating valve I , combined with the valve E , and actuated thereby through the jointed connection $M L$, or its equivalent, substantially as hereinbefore set forth.

2. The cam x and bearing u' , arranged and operating with the measuring-wheel Q , as and for the purpose hereinbefore set forth.

J. P. SMITH.
